FURNACE

Leif Lee, Youngstown, Ohio

Application April 19, 1934, Serial No. 721,301

2 Claims. (Cl. 263—6)

This invention relates to furnaces and method of operating the same and is herein specifically described as applied to a furnace for the heat treatment, e. g., normalizing, of sheets. It will be understood, however, that this is by way of example only and that the invention has numerous other applications.

In heating furnaces, particularly those of the continuous type, the problem of supporting the work is always a difficult one. It is necessary to support it in such fashion that the work will be uniformly heated and that it will not have "black spots" or similar local areas which have been chilled by contact with the supporting surfaces. Numerous schemes have been proposed for supporting the work, many of them involving soaking hearths beyond the supporting skids or rails. Other proposals have required the use of expensive heat resisting alloys which can be brought up to sufficiently high temperature that they will not unduly affect the work and yet have sufficient strength to support the load. Rolls, walking beams, and various other devices have been proposed, but all of them, as heretofore constructed, have been open to numerous objections, particularly from the point of view of maintaining their strength under the high temperature conditions existing.

I overcome these difficulties and at the same time effect a considerable simplicity in design of the furnace mechanism by my invention. Briefly stated, I provide for tensioning the work supporting members and maintaining this tension sufficiently high to substantially eliminate distortion of the work supporting members. This tensioning may be carried out in a variety of ways, but I prefer to use weights because of the simplicity of construction, the fact that the tension may be readily adjusted by changing the value of the tensioning weights, and that the tension so secured is constant at all times. Springs or other devices might be used but they are open to numerous objections. Springs, for instance, might relax because of the heat adjacent the furnace. The invention may be conveniently applied to a furnace of the walking beam type, in which case the work supporting beams are tensioned longitudinally of the furnace.

In the accompanying drawings illustrating a present preferred embodiment of my invention and certain modifications thereof,

Figure 1 is a side elevation of the furnace with the center portion broken away;

Figure 2 is a longitudinal vertical section;

Figure 3 is a horizontal section taken on the line III—III of Figure 2;

Figure 4 is a transverse section taken on the line IV—IV of Figure 2; and

Figures 5 and 6 are fragmentary vertical longitudinal sections showing a modified structure.

The furnace shown in Figures 1 to 4 constitutes a furnace chamber 2 made of suitable refractory to form a bottom 3, roof 4 and side walls 5 and 6 contained within a binder 7. The furnace is heated by burners 8 discharging into the chamber 2 and recirculating flues 9.

The work, which is illustrated in this case as being in the form of steel sheets S, is carried through the furnace chamber by means of a walking beam apparatus. This apparatus comprises fixed bars 10 and movable bars 11. The bars 10 extend the major portion of the length of the furnace through which the work advances in the direction of the arrow A (Figure 2) and at their forward ends are hooked around a cross beam 12. They are supported at intermediate points on stools 13 carried by piers 14 in the furnace. Their rear ends 10a project from the entering end of the furnace and are connected by cables 15 running over pulleys 16 and carrying tensioning weights 17. These weights serve to keep the bars 10 stretched and prevent distortion thereof. Even though the bars are made of material not ordinarily considered as heat resistant, or made of material intended to work only in zones of relatively low temperature, they nevertheless will withstand furnace conditions exceptionally well because, being so tensioned, they do not droop or otherwise distort under their own weight or under the weight of the work 30 placed upon them.

The work is advanced through the furnace by means of the movable bars 11. Such bars are supported by rollers 18 mounted on cross shafts 19 extending through slots 20 in the furnace walls and journaled in bearings 21. The bearings 21 are supported on I-beams 22 extending alongside the furnace. Raising and lowering of the I-beams 22 of course serves to raise and lower the rollers 18 and the bars 11 carried thereby. Provision is also made for moving the bars 11 backwards and forwards in the furnace chamber. The longitudinal movement and the raising and lowering movement of the bars are effected in such manner as to advance the work 45 through the furnace. This is done by raising the bars 11 above the level of the bars 10, thereby lifting the work, then moving the bars 11 forward, then lowering them below the level of the bars 10 so as to deposit the work thereon, then moving the 50 bars 11 rearwardly while still in the lowered position, and then raising them to again lift the work from the stationary bars 10 for another advancing movement. The mechanism for effecting these movements is hereinafter described. 55

The bars 10 and 11 will not ordinarily require cooling and this is of advantage because local chilling of the work is thereby avoided; but it will be understood that, if desired, some cooling may be effected as, for example, by circulating a 60

liquid or gas through the bars. Likewise, the shafts 19 may be cooled. It will be understood that cooling of the shafts 19 will not effect local chilling of the work.

5 The raising and lowering of the bars 11 is effected by means of wedges 23 operating between rollers 24 mounted on the beams 22 and fixed rolls 25 mounted on piers 26 alongside the furnace. The wedges 23 are carried by longitudinally extending beams 27 and movement of the beams 27 in one direction or the other serves to raise and lower the beams 22. Longitudinal movement of the beams 22 is prevented by tongues 28 secured to the beams 22 and extending downwardly between rollers 29 carried in fixed brackets 30. The beams 27 are connected at their ends through links 31 to levers 32 fixed on a rock-shaft 33. The rock-shaft 33 carries an arm 34 having a roller which engages a cam 35. The cam is carried on a shaft 36 connected through gearing 37 to a motor 38. At their other ends the beams 27 are connected to cables 39 running over pulleys 40 and carrying counterweights 41. As the cam shaft 36 rotates, the arms 32 are rocked clockwise, as viewed in Figure 2, thereby moving the beams 27 from left to right and raising the beams 22 and hence the movable bars 11. Continued rotation of the cam shaft permits the arms 32 to rock counter-clockwise, the weight 41 moving the bars 27 to the left as rapidly as the cam 35 permits and thereby causing lowering of the bars 11.

The motor 38 also drives the mechanism which moves the bars 11 longitudinally so that the vertical and longitudinal movements of the bars are properly synchronized. At the entering end of the furnace the bars 11 are connected to cables 42. These cables run over a multiplying pulley system 43 and through it support counterweights 44. The system of multiplying pulleys is used so as to allow a long stroke of the bars 11 while limiting the vertical movement of the counterweights 44. This reduces the pit depth required. At their forward ends the bars 11 have their noses turned down, as indicated at 11a, for connection to chains 45 which are dead-ended at 46 on sector arms 47. These arms are secured to a rock-shaft 48, which also has an arm 49 thereon. The arm 49 is connected through a link 50 to an arm 51 on a rock-shaft 52. The rock-shaft 52 carries an arm 53 having a cam roller 54 thereon engaging a cam 55 on a shaft 56, which shaft is connected through gearing 57 to the motor 38. As stated, the movements of the bars 11 are thus synchronized so as to get the proper feeding motion of the work through the furnace.

After the work passes the forward ends of the bars 10 it is lowered upon lowering of the bars 11 onto chains 58 which effect its discharge from the furnace. These chains extend into the furnace and are connected at their inner ends to

counterweights 59. They run over pulleys 60 and 61 and then extend downwardly and are dead-ended at 62 to sprocket wheels 63 on a shaft 64. The shaft 64 is connected through a slide-link mechanism 65 to the arm 66 of a crank 5 67 driven through speed reducing mechanism 68 by a motor 69. When the bars 11 deposit work on the chains 58 the motor 68 rotates the sprocket 63 clockwise, as viewed in the drawings, thereby causing the chains 58 to move forward and carry 10 the work out of the furnace. It is thereby deposited on the chains 45 and may be taken away by hand or by any convenient mechanism.

Figures 5 and 6 illustrate modified constructions wherein the work is held in the furnace 15 adjacent the entering end thereof for some period before being carried through the main body of the furnace on the tensioned bars. In Figure 5 I have shown a pair of spaced sprockets 70 and 71 supporting chains 72 to which arms 20 73 are connected. The work is fed in at 74 and fed by the bars 11b onto a pair of the arms 73. The sprockets 70 and 71 are then advanced so as to move these arms upwardly by one step. The next sheet is fed between the succeeding pair of arms and so on, the pieces being carried up over the sprocket 71 and then down until they are deposited on the bars at 75 and thence carried forward through the furnace. In Figure 6 a spider 76 serves the same purpose.

I have illustrated and described present preferred embodiments of my invention. It will be understood, however, that this is by way of illustration only and that it may be otherwise embodied within the scope of the following claims.

I claim:

1. In a furnace, work supporting members, means for moving certain of said members relative to others to advance work through the furnace, means engaging the movable work supporting members adjacent one end and exerting a pull thereon so as to maintain them under tension, reciprocable supporting members disposed for receiving the work advanced by said movable members and for discharging the work from the furnace, and means for actuating said reciprocable members.

2. In a furnace, a work supporting member, means for securing one end thereof, a work supporting member movable relative to said secured member, actuating means engaging an end portion of the movable member and movable back and forth to effect relative movement between said work supporting members thereby advancing the work through the furnace, means engaging said work supporting members and exerting a pull on each so as to maintain them under tension, reciprocable chains disposed for receiving the work advanced through the furnace by the relative movement between said members, and means for reciprocating said chains to discharge the work from the furnace.

LEIF LEE.
